UNITED STATES PATENT OFFICE.

VINTON E. SISSON, OF CHICAGO, ILLINOIS, ASSIGNOR TO UNION METAL PRODUCTS COMPANY, OF CHICAGO, ILLINOIS, A CORPORATION OF DELAWARE.

CORRUGATED WALL PLATE.

Application filed December 9, 1922. Serial No. 605,931.

To all whom it may concern:

Be it known that I, VINTON E. SISSON, residing at Chicago, county of Cook, State of Illinois, and being a citizen of the United States, have invented certain new and useful Improvements in Corrugated Wall Plate, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

My invention has for its object to provide an all metal car construction of novel character which is unusually strong for its weight and durable throughout, which may be conveniently and economically manufactured and transported, is weatherproof and which possess certain other desirable and advantageous features to be hereinafter described and claimed. My sheet metal wall structure is applicable to box, automobile, gondola, stock or any other type of railway equipment.

The ends of railway cars are subject to considerable stress due to the shifting of the lading. These blows are imparted to the end over the entire area thereof, or to local or concentrated thrust. Corn is loaded to substantially the top of the car which causes all the blow to be imparted over the entire area of the end. Lumber is loaded to the top and upon impact the top boards shift causing a blow to be imparted at the top of the end. Sand, chats and other plastic loads and light pipe cause blows at the middle of the car, whereas rail, steel plates, castings and the like cause blows at the bottom of the car. From the above it will be apparent that a railway car end must have practically the same strength at any part thereof.

While, of course, efforts are made to block the lading in the car, the heavy locomotives, the emergency air brake and the classification hump break the lading away from its moorings and throw it against the end of the car.

55 A rigid end to a car, and particularly a

large box car, materially strengthens the entire superstructure to resist the torsional and weaving movements which not only rack the car to pieces, but causes leaky roofs and inoperative and leaky doors with their consequent damage claims. As it costs as much to transport a ton of freight car as it does a ton of lading it is imperative that the weight of the car must be kept as low as possible, therefore, the end must be very light as well as strong. As freight cars are frequently damaged in wrecks and by other unfair usage, any end will be damaged in service, therefore, it must be capable of being easily repaired with such meagre facilities as the railroads are equipped with at their outlying repair points.

Car wall structures have been manufactured and are in extensive use wherein a series of straight parallel corrugations are formed in the plate which terminate within the edge thereof to form flat margins. Each corrugation is a beam and transmits any load imposed upon it to the corrugation on either side of it and to the side wall of the car. Such structures are claimed in my Patent No. 1,271,234, Reissue No. 14,434 and others; the Murphy-Sisson Patent No. 1,031,571 and other patents to Murphy.

It has been found in this present commercial end that when a local thrust deflects one corrugation that the adjacent parallel corrugation also deflects proportionately, thereby cooperating to resist such thrust. Many loads, such as planed lumber and steel plate, exert a thrust along a horizontal line, therefore, such thrust is exerted upon one corrugation.

The invention herein claimed consists in having the corrugations substantially parallel or spaced equidistantly apart, and at the same time having them curved or otherwise deflected, whereby any straight line, such as 2—2, 3—3, 10—10 or 11—11 in Fig. 1 crosses two or more corrugations or crosses one of the corrugations twice. At the same time the corrugations terminate within the edge of the sheet adjacent the corner post so that they constitute a series of cooperating beams.

This arrangement gives the corrugated plate additional strength and at the same time retains the resiliency and other advantages of the present commercial end.

I have shown and described my improve-

ment with the corrugations positioned horizontally but they may be positioned vertically or obliquely. Furthermore, the wall may be made of one or a plurality of plates 5 connected along horizontal, vertical or oblique lines. Furthermore, the construction may be applied to the side or end wall of a box, gondola, or any other type of railway car, or the cross sectional contour of 10 the corrugations may be of any desired contour, or pressed from either side of the plate or partially from both sides, and still come within the scope of the invention.

In the drawings:

15 Fig. 1 shows a front elevation of a box car with my improved wall applied thereon wherein the corrugations are formed on reversed curves.

Fig. 2 is a cross section along the line 20 2—2 of Fig. 1.

Fig. 3 is a cross section along the line 3—3 of Fig. 1.

Fig. 4 is a front elevation of a box car with the modification of my invention applied thereon wherein the corrugations are 25 formed on arcs.

Fig. 5 is a cross section along the line 5—5 of Fig. 4.

Fig. 6 is a cross section along the line 30 6—6 of Fig. 4.

Fig. 7 is an end elevation of a box car with my improvement applied thereon wherein the corrugations are formed of a series of straight lines. Furthermore, the 35 corrugations extend to the edge of the plate.

Fig. 8 is a cross section along the line 8—8 of Fig. 7.

Fig. 9 is a cross section along the line 9—9 of Fig. 7.

40 In Figs. 1, 4 and 7 it will be noted that the corrugations are spaced substantially equal distances apart and that they are deflected from a straight line so that any straight line drawn across the plate crosses one corrugation twice or crosses two corrugations.

45 The corrugations are spaced substantially equal distances apart, it not being necessary that they be parallel or exact equal distances apart to accomplish the purpose of the invention.

50 In the drawings numerals 1 and 2 are the plates having the above described corrugations formed therein; 3 the corner post; 4 the end sill angle; 5 the flange forming the 55 end plate; 6 the center sills; 7 the striking casting; 8 the side and end sill connecting pieces; 9 the lining boards and 10 the lining board nailing strips, all of which are parts of a usual car.

60 In Figs. 1 and 2 the corrugations 12 are formed on a reversed curve.

In Figs. 4 and 5 the corrugations 13 are formed on an arc and in Figs. 7 and 8 the

corrugations 14 are formed by straight lines. However, any combination of curves 65 or straight lines may be used and yet come within the scope of this invention, provided they are so arranged and positioned whereby any straight line drawn across the plate crosses one corrugation twice or crosses two 70 corrugations.

What I claim is:

1. In a wall for railway cars, a metallic plate having a plurality of corrugations formed therein extending from opposite edges 75 of the plate, said corrugations deflected from a straight line whereby any straight line drawn across the plate crosses one corrugation at least twice or crosses at least two corrugations.

2. In a wall for railway cars, a metallic plate having a plurality of corrugations formed therein terminating within, and extending substantially from opposite edges of the plate, said corrugations deflected from 85 a straight line whereby any straight line drawn across the plate crosses one corrugation at least twice or crosses at least two corrugations.

3. In a wall for railway cars, a metallic 90 plate having a plurality of corrugations formed therein, spaced substantially equal distances apart, extending substantially from opposite edges of the plate, said corrugations deflected from a straight line 95 whereby any straight line drawn across the plate crosses one corrugation at least twice or crosses at least two corrugations.

4. In a wall for railway car, a metallic plate having a plurality of corrugations 100 formed therein, spaced substantially equal distances apart, terminating within said corrugations deflected from a straight line whereby any straight line drawn across the plate crosses one corrugation at least twice 105 or crosses at least two corrugations.

5. In a wall for railway car, a metallic plate having a plurality of corrugations formed therein, terminating within the edges of the plate, said corrugations deflected from a straight line whereby any straight line drawn across the plate crosses one corrugation at least twice or crosses at least two corrugations.

6. In a wall for railway cars, a metallic 115 plate having a plurality of corrugations formed therein, spaced substantially equal distances apart, terminating within the edge of the plate, and extending substantially from opposite edges of the plate, said corrugations deflected from a straight line whereby any straight line drawn across the plate crosses one corrugation at least twice 120 or crosses at least two corrugations.

VINTON E. SISSON.
